ADAM F. BUTCH

334 Francis J. Kempf

arms 29 between the upper ends of which is positioned an apertured member 30 for receiving a shaft 31. Pivotally mounted between the side walls of the channel 28 is a double bellcrank lever 32, the short upwardly extending leg of which is screw-threadedly connected at 33 with a screw-thread portion of the shaft 31. To the opposite end of the shaft 31 is secured a hand-wheel 34 and suitable collars prevent axial movement of the shaft 31 relative to the arms 29. Therefore, rotation of the hand-wheel 34 will result in rocking movement of the lever 32 and such movement of this lever is utilized to tilt the scraper blade of the assembly. For this latter purpose outwardly extending channel spurs 35 are welded 15 to the side surfaces of the members 23 below the lever 32. An aperture is formed in the outer end portion of the horizontal web of each of the spurs 35 to slidably receive a bolt 36. The upper ends of the bolts 36 are rigidly connected to yokes 37 which in turn are pivotally connected to the outer ends of the lever 32 by means of the links 38. Interposed between the yokes 37 and the spurs 35 and encircling the bolts 36 are the coil springs 39. An adjustable nut 40 is threaded onto the lower end of each of the bolts 36 below the spurs 35; and the springs 39 are of such strength that normally the nuts 40 are in contact with the spurs 35. However, upon the scraper blade hitting an unusual obstruction the blade can rise 30 against the action of the springs 39 thereby avoiding breakage of any of the parts of the assembly. Extending rearwardly and downwardly from the fitting 21' and rigidly secured thereto is a pair of spaced parallel plates 41 adapted to enter in-between the spaced members 23. Wear-resistant nobs 42 may be welded to the outer side surfaces of the plates 41 to engage the members 23. In this manner lateral movement of the scraper blade with respect to the carrier frame 11-18, aside from the adjustment now to be described, is prevented.

Fitting 21' is formed with spaced parallel upper and lower plates which overlie the outer surfaces of the horizontal flanges of the beam 11 and to clamp the fitting in adjusted position along the beam 11 as well as to guide the fitting with respect to the beam I provide four bolts 43 which pass through these spaced plates and pull the same together. Further, I may provide a series of spaced arcuately disposed apertures 44 in the beam 11 to selectively receive a pin 45 which passes down through both the spaced parallel plates of the fitting 21'. By loosening the bolts 43 and removing the pin 45 the fitting 21' may be moved along the beam 11 in an arcuate path concentric about the pin 20 to any one of a number of adjusted positions and in this manner the angularity of the scraper blade with respect to the line of travel of the pulling vehicle may be varied as desired to move the matter being graded to the right or to the left as desired. The pin 45 by passing through the fitting 21' and the selected aperture in the beam 11 will positively maintain the adjusted position of the parts. In accordance with usual practice the scraper blade 22 may be provided with a hardened steel cutting edge member 46.

As explained more fully in the above mentioned copending application, the principle carrier frame of the assembly is arranged to be raised and lowered by tilting movement of the dump truck body. For this purpose a pair of spaced parallel tubes 47 project rearwardly from the tilting body 48 of the motor truck. The rear ends of the tubes

47 project through apertures provided in fittings 49 which are rigidly connected to the top surface of the outer ends of the beam 11. I also preferably provide readily removable pins 50 to interlock the tubes 47 with the fittings 49. As described in my earlier application, the tubes 47 are mounted in sockets on the body 48 and are free to slide longitudinally with respect to the body. This facilitates the attachment of the scraper assembly to the motor truck and upon tilting movement of the body 48 the carrier frame or boom of the scraper assembly will be moved upwardly or downwardly as will be understood. Likewise, the required pressure-loading of the scraper blade is accomplished by downward forces transmitted through the tubes 47 upon upward tilting movement of the body 48.

Slidably received in a socket 51 which is secured to the frame member 18 is a supporting standard 52 having a pad 53 at its lower end. Member 52 is formed of a tube length and has spaced apertures to selectively receive a removable pin whereby the standard may be maintained in elevated inoperative position when the scraper assembly is attached to the motor truck or in lower frame supporting position when the scraper attachment is removed from the truck as will be readily understood.

A lug 55 extends downwardly from the forward end of each of the side rails 10 and pivotally mounted on these lugs by means of the rod 56 is a pair of spaced parallel side rails 57 of a frame carrying a scarifier comprised of a series of transversely spaced hardened and sharpened teeth 58 which are operative to loosen compacted earth, shale, etc., ahead of the scraper blade. Teeth 58 are carried by a structural member 59 which is attached to the rear ends of the arms 57 and pivotally connected with the member 59 at transversely spaced points is a pair of upwardly extending bars 60 which are apertured at spaced points as shown at 61. Apertured webs 62 are welded in the channel 15 on opposite sides of the bar 60 to receive pins 63 which pass through certain of the apertures 61. In this manner the scarifier may be securely locked in adjusted vertical position. To assist in raising and lowering the scarifier assembly I may provide a winch comprising a cable receiving drum 64 keyed to a shaft 65 which is journaled on the side rails 10. A handcrank 66 is provided to rotate the shaft 65 and consequently the drum 64 to take up a cable 67, the lower end of which is attached to the pivoted scarifier frame.

It should now be apparent that I have provided an improved road grading attachment for conventional motor trucks of the load-dumping type which accomplishes various desired objectives including those mentioned above. While the component sections of the assembly are sufficiently heavy to lend required strength and rigidity, the arrangement is such that the assembly may be operated entirely by one man, including the attachment and detachment of the assembly with respect to the truck. Moreover, the scraper blade is provided with such adjustments as are necessary or desirable in laterally distributing the matter being graded and in effecting any desired crown or slope in the finished matter. Further, the component parts of the assembly are easily produced from stock materials and are of such design that they may be expeditiously assembled, primarily by welding, into the completed attachment.

The above specifically described embodiment of

the invention should be considered as illustrative only as obviously many changes may be made therein without departing from the spirit or scope of the invention. Reference should therefore be had to the appended claims in determining the scope of the invention.

What I claim is:

1. In a road grading attachment having a boom adapted to be pivotally connected to the frame of a motor dump truck and means adapted to be coupled with the body of the truck and movable therewith to raise and lower said boom, the combination of a transversely extending scraper blade, means mounting said scraper blade comprising an arm extending upwardly and forwardly underneath the rear portion of said boom, a vertically disposed pivot pin carried by said boom, loose connecting means for anchoring the forward end of said arm to said pivot pin, means to adjust the position of said arm and blade about said pivot pin, and means to tilt said blade about the longitudinal axis of said boom.

2. In a road grading attachment having a boom adapted to be pivotally connected to the frame of a motor dump truck and means adapted to be coupled with the body of the truck and movable therewith to raise and lower said boom, the improvement consisting of constructing said boom of a pair of spaced side rails having means at their forward ends for pivotal attachment to said frame, a rearwardly curved beam interconnecting the rear ends of said side rails, a fitting slidable long said beam, a scraper blade, an arm mounting said blade and having its forward end pivotally coupled with said boom, and means interconnecting said arm and fitting whereby the lateral position and angular relation of said blade with respect to said boom may be varied.

3. In a road grading attachment having a boom adapted to be pivotally connected to the frame of a motor dump truck and means adapted to be coupled with the body of the truck and movable therewith to raise and lower said boom, the improvement consisting of providing said boom with a rearwardly curved but generally transverse beam, a fitting slidably mounted on said beam, means to lock said fitting in adjusted position on said beam, a scraper blade, an arm mounting said blade and having its forward end pivotally coupled with said boom, and means interconnecting said arm and fitting whereby the lateral and angular relation of said blade with respect to said boom may be varied.

4. In a road grading attachment having a boom adapted to be pivotally connected to the frame of a motor dump truck and means adapted to be coupled with the body of the truck and movable therewith to raise and lower said boom, the combination of a scraper blade, an upwardly and forwardly curved arm mounting said blade and extending underneath a portion of said boom, means pivotally connecting the forward end of said arm to the center portion of said boom whereby said arm may have limited turning movement about longitudinal and vertical axes, a lever pivoted on the rear portion of said boom

and having oppositely disposed arms connected with laterally disposed spurs extending outwardly from said first mentioned arm, and means comprising a handwheel and a screw attached thereto for rocking said lever whereby said scraper blade may be tilted about said longitudinal axis.

5. Apparatus according to claim 4 further including yieldable interconnections between said spurs and the arms of said lever.

6. Apparatus according to claim 4 further characterized in that said lever is pivotally mounted on a fitting carried by the rear end portion of said boom, the means mounting said fitting of said boom being operative to provide for position adjustment of said fitting along an arcuate path concentric about the vertical pivotal axis of the interconnection between said boom and the forward end of said first mentioned arm.

7. Apparatus of the character described comprising in combination a boom adapted to be pivotally attached to a motor truck, said boom having side rails and a transverse channel member spanning said side rails intermediate the ends thereof, a yoke rigidly secured to the undersurface of the center portion of said channel member, a vertically disposed pivot pin held a spaced points in said yoke and channel member, an anchor block pivotally mounted on said pin, a scraper blade, a hook-like arm mounting said blade and having a bifurcated forward end positioned about said block, a transverse pin extending through said block and the bifurcations of said arm forwardly of said first mentioned pin, and means to maintain said arm in adjusted positions about the axis of said first mentioned pin.

8. Apparatus according to claim 7 further characterized in that said means to maintain comprises a rearwardly curved beam interconnecting the rear ends of said side rails and a fitting adjustably mounted on said beam and engaging said arm, said transverse pin being loosely received in said block, and means on said fitting to tilt said arm whereby either end of said blade may be raised with respect to the opposite end thereof.
